LIFEBOAT LAUNCHING APPARATUS

John L. Hyland, New York, N. Y.

Application May 17, 1930, Serial No. 453,393

9 Claims.

(Cl. 9—22)

This invention relates to an improvement in life boat launching apparatus.

The object of the invention is to simplify and improve the manner of launching life boats from the decks of ships, so that one man may launch the boat from the side of the ship regardless of the listing of the ship, and the boat may be launched from the high side of the listing ship in less time than is ordinarily required on the lower side.

In the accompanying drawings:

Fig. 1 is a side elevation showing the deck of the ship in section and illustrating the apparatus for launching the life boat;

Fig. 2 is a top plan view thereof, partly in section and with a part of a cover for the life boat broken away;

Fig. 3 is a transverse vertical section through a portion of the apparatus;

Fig. 4 is a sectional view at right angles thereto through the complete apparatus;

Fig. 5 is a detail sectional view showing the manner of attaching the rope to the shaft therefor, and

Fig. 6 is a detail sectional view showing the supporting arms in elevation, with parts omitted for the sake of clearness.

The deck of the ship is designated generally by the numeral 1 and a wall or cabin is shown at 2. The life boat 3 is adapted to be supported in an upright position above and upon the deck 1, so that it may be pushed over the side of the ship and lowered to the surface of the water. As a means of accomplishing this, a frame 4 is mounted upon the deck 1 and has a curved edge 5 and notch 6 outwardly presented to normally receive and support the life boat 3 as shown in Figs. 1 and 4.

Mounted in a pivotally supported horizontal frame 7 is a shaft 8 having its periphery grooved as at 9 (see Figs. 2 and 5) to receive ropes 10 which are coiled thereon in opposite directions. The inner ends of the ropes are removably attached to the shaft 8 by means of pins 11, as shown in detail in Fig. 5. The lower ends of the ropes 10 carry hooks 12, shown in dotted lines in Fig. 4, which are received by eyelets 13 secured to a shaft 14 extending longitudinally through the life boat 3.

The frame 7 is pivoted to the upper ends of arms 15, which are in turn pivoted at their lower ends as at 16 to the frame 4, which arms serve to support the life boat as it is swung from the full line position in Fig. 1 to the dotted line position. The frame 7 also has legs 17 extending

downwardly therefrom to rest on the deck 1 in the dotted line position in Fig. 1 and on spacers 18 within the frame 4, when in the full line position of Fig. 1 and as also shown in Fig. 3.

As a means of winding and unwinding the ropes 10 and for turning the shaft 8, a gear 19 is fixed to said shaft as shown in Fig. 4, meshing with a gear 20 fixed on the shaft 21 extending parallel with the shaft 8, and which gear 20 is driven through a train of gears designated 10 generally by the numeral 21 from a worm 22 attached to a stub shaft 23, and which in turn is rotated by a hand-wheel 24. Upon turning the hand-wheel, the shaft 8 is rotated in the proper direction for winding or unwinding the rope 10 to raise or lower the life boat. By reason of the use of the worm 22 as the driving means for the gearing, this acts as a brake preventing rotation of the gearing by the weight of the life-boat, and only when the hand-wheel 24 is turned, so that the hand-wheel 24 must be positively rotated to permit the unwinding of the ropes in order that the weight of the life boat will not of itself cause an unwinding of the ropes.

A casing 25 incloses the gearing and is connected at its upper end with the frame 7 and also with a cover 26 which encloses the top of the life boat.

As an additional means of winding up the ropes 10 and to give added power for that purpose, a shaft 27 is fixed to one of the gears 21 and extends through the frame 7, being carried thereby, which shaft 27 has pins 28 slidably mounted in the opposite ends thereof to permit manually turning this shaft and winding up the ropes and to assist the gearing for this purpose.

A sleeve 29 is fixed to the frame 7 and is internally threaded to receive a screw 30 secured to a hand-wheel 31, which also has a threaded screw 32 secured thereto and received within an internally threaded bushing 33, suitably mounted in a side of the wall 2 or other support but fixed against endwise movement.

The screws 29 and 32 are oppositely threaded as shown in Fig. 4 so as to provide a double movement upon the rotation of the hand-wheel 31 causing an outward feeding action of the sleeve 29. Guides 34 are fixed to the frame 7 and are provided with curved slots 35 therein to receive guide pins 36 fixed to the frame 4 for guiding the outward movement of the frame.

In the operation of the device, the life boat is normally in the position shown in full lines in Fig. 1 and disposed on the deck of the ship in upright position protected by the cover 26. The

parts are entirely inclosed so as to be free from injury by the elements.

When it is desired to lower the life boat, the hand-wheel 31 is rotated, which causes the entire frame 7 with its connected parts to be moved forward over the deck 1 to the dotted line position shown in Fig. 1. The operator then turns the hand-wheel 24, which, through the gearing, unwinds the ropes 10, lowering the life boat to the surface of the water. The ropes are preferably released from the life boat by releasing the hooks 12, but if for any reason they are not released, as that no one is in the life boat, the continual unwinding of the ropes will cause them to be automatically released from the pins 11 attached to the shaft 8 and over which pins the loop ends of the ropes are received.

The worm 22 acts as a brake in lowering the life boat, preventing the weight of the life boat from automatically causing an unwinding of the ropes.

In this way, one man may quickly move the life boat off of the ship and launch it without any assistance and in less time than is ordinarily required for the purpose. The construction is such as to permit the life boat to be launched even when the ship is listing and from the high side thereof.

I claim:

- 30 1. In a lifeboat launching apparatus, the combination of a support, arms pivoted to the support, portions of the arms having depending legs carried thereby in positions to swing with the arms from one side of the pivots to the other side of the pivots, means disposed on opposite sides of the pivots in position to receive the legs for supporting the legs in different positions of the arms, and means for supporting a lifeboat from the arms.
- 40 2. In a lifeboat launching apparatus, the combination of an upright support having a shoultered portion for receiving and supporting a lifeboat in upright position, arms pivoted to the lower portion of said support, the upper portions of the arms having depending legs carried thereby, means for supporting the legs in different positions of the arms, and means for supporting a lifeboat from the arms.
- 50 3. In a lifeboat launching apparatus, the combination of a support, arms pivoted to the lower portion of the support, the upper portions of the arms having depending supporting legs carried thereby in positions to swing with the arms from one side of the pivots to the other side of the pivots, seats on opposite sides of the pivots for receiving and supporting the legs in a reclined position of the arms, and means for supporting a lifeboat from the arms.
- 60 4. In lifeboat launching apparatus, the combination of supporting means, arms pivoted to the supporting means, an approximately horizontal frame pivotally carried by said arms, means for holding said frame approximately horizontal during swinging movement of the arms, means for suspending a lifeboat from said

frame, and means for causing an outward swinging movement of the arms to move the lifeboat to a lowering position.

5. In lifeboat launching apparatus, the combination of an upright supporting frame, arms pivoted to the lower portion of the frame, a horizontal frame pivotally carried by said arms, means for suspending a lifeboat from said last-mentioned frame, and means connected with said last-mentioned frame for causing an outward swinging movement of the arms to move the lifeboat to a lowering position.

6. In lifeboat launching apparatus, the combination of an upright supporting frame, arms pivoted to the lower portion of the frame, a horizontal frame pivotally carried by said arms and having depending supporting legs, means for suspending a lifeboat from said last-mentioned frame, and means connected with said last-mentioned frame for causing an outward swinging movement of the arms to move the lifeboat to a lowering position.

7. In lifeboat launching apparatus, the combination of a support having a stationary lifeboat seat therein, supporting structure pivoted to the support at a point directly below the seat and extending around and over the seat in position to embrace a lifeboat supported on the seat in upright position, and means carried by said supporting structure in position to be disposed over the lifeboat when seated for supporting the lifeboat.

8. In a lifeboat launching apparatus, the combination of fixed supporting structure, movable frame structure, means supporting said movable frame structure on the fixed supporting structure for movement between a retracted position and a forward lifeboat launching position, means for holding the movable frame structure substantially horizontal during said movement, a rigid lifeboat cover permanently secured to the movable frame structure in position to overlie the lifeboat, and means carried by the movable frame structure for supporting the lifeboat beneath the cover and for lowering the lifeboat away from the cover without removal of the cover.

9. In lifeboat launching apparatus, the combination of fixed supporting structure, movable frame structure, arms pivoted to the fixed supporting structure and pivotally supporting the movable frame structure for movement between a retracted position and a forward lifeboat launching position, guides attached to the movable frame structure and holding the same substantially horizontal during said movement, a rigid lifeboat cover permanently secured to the movable frame structure in position to overlie the lifeboat, and means carried by the movable frame structure for supporting the lifeboat beneath the cover and for lowering the lifeboat away from the cover without removal of the cover.
